CLAIM

The ornamental design for a tire pressure relearn tool, as shown and described.

DESCRIPTION

FIG. 1 is a front perspective view of a tire pressure relearn tool showing my new design;

FIG. 2 is rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1; and,

FIG. 10 is a partial enlarged view of FIG. 2.

The broken lines in the figures are for the purposes of illustrating portions of the tire pressure relearn tool, which form no part of the claimed design.
